VAPORIZING APPARATUS

Amos N. Somers, Westboro, Mass.

Application November 24, 1937, Serial No. 176,268

1 Claim. (Cl. 123—119)

This invention relates to internal combustion engines in which liquid fuel such as gasoline is vaporized by passage through a carburetor. My invention relates particularly to certain improved apparatus for supplying air to a carburetor and for maintaining a predetermined and uniform excess air pressure on the intake of said carburetor.

My invention further relates to arrangements and combinations of parts which will be herein-after described and more particularly pointed out in the appended claim.

A preferred form of the invention is shown in the drawing, in which—

Fig. 1 is a side elevation of parts of an internal combustion engine having my improvements applied thereto;

Fig. 2 is an enlarged side elevation, partly in section, of certain parts appearing in Fig. 1 and embodying my invention;

Fig. 3 is a plan view of the parts shown in Fig. 2;

Fig. 4 is an enlarged side elevation of a relief valve structure; and

Fig. 5 is an end view thereof, looking in the direction of the arrow 5 in Fig. 4.

Referring to Fig. 1, I have shown portions of an internal combustion engine 10 provided with the usual air circulating fan 11, positioned adjacent the rear face of a radiator 12, indicated in broken lines. The engine 10 is also provided with the usual gas intake 14 having an uptake 15, connected at its lower end to a carburetor 16 which has an air intake 17 and a gasoline supply connection 18.

The parts thus far described, in and of themselves, form no part of my present invention and may be of any usual or commercial type.

For the purposes of my invention, I provide an air storage chamber 20 mounted on or freely connected with the air intake 17 of the carburetor 16. A pipe or conduit 22 extends forward from the chamber 20 and is preferably provided with an enlarged or bell-shaped forward end 23, which is located just at the rear of the fan 11 and in the path of the air blast drawn through the radiator 12. A screen or air filter 24 is provided in the enlarged front end portion 23 of the pipe 22.

The air chamber 20 is provided with a relief pipe 30 having an outwardly opening relief valve 31 (Figs. 4 and 5), yieldingly moved to normal closed position by a spring 32. The air chamber 20 may also have a removable cap 33, so that the interior of the chamber may be accessible for cleaning.

When the engine 10 and fan 11 are in operation, a strong current of fresh and relatively cool

air enters the enlarged or bell-shaped end 23 of the pipe 22 and is forced through the pipe to the air chamber 20. This air chamber 20 is of such capacity that a substantial amount of this fresh air will be banked or stored therein. This fresh air is maintained at excess pressure, slightly above atmospheric, by the action of the fan 11.

The excess pressure is regulated and held substantially uniform by the relief valve 31 on the relief pipe 30. When the air pressure rises to a predetermined point, the valve 31 opens and further rise in pressure is prevented.

It is thus evident that my improved apparatus provides a fresh air supply for the carburetor 16 which is ample in volume and which is uniformly maintained at a predetermined excess pressure slightly above atmospheric. Furthermore, this fresh cool air retains a substantially larger moisture content than hot air taken from the immediate vicinity of the highly heated engine, which is the usual practice.

It has been found by actual test that an engine in which the carburetor is supplied with cool fresh air according to my invention and under slight excess pressure develops substantially increased power from a given amount of fuel, produces less carbon, starts quicker and runs more smoothly. The percentage of carbon monoxide is also substantially reduced.

Having thus described my invention and the advantages thereof, I do not wish to be limited to the details herein disclosed, otherwise than as set forth in the claim, but what I claim is:

Vaporizing apparatus for an internal combustion engine having a cooling fan, comprising a carburetor having an air intake, a vertical cylindrical air storage chamber of substantial capacity freely connected through its bottom to said carburetor intake, said storage chamber being of greater horizontal diameter than vertical length and having a removable top cover to facilitate cleaning, an air supply pipe for said chamber having an enlarged front end positioned adjacent the rear face of said fan and in the blast of air therefrom and having its rear end connected into the front side wall of said storage chamber, said supply pipe being of very much less diameter than said storage chamber, an air filter in said air supply pipe, a relatively small vent pipe extending outward from the rear wall of said storage chamber, and a yielding relief valve mounted at the outer end of said vent pipe and effective to maintain the excess air pressure produced by said air blast in said storage chamber at a predetermined and constant amount.
